UNITED STATES PATENT OFFICE.

SEYMOUR K. SEELYE, OF HUDSON, MICHIGAN.

STRETCHER FOR ENDLESS CARRIERS.

SPECIFICATION forming part of Letters Patent No. 355,723, dated January 11, 1887.

Application filed February 11, 1886. Serial No. 191,601. (No model.)

To all whom it may concern:

Be it known that I, SEYMOUR K. SEELYE, a citizen of the United States, residing at Hudson, in the county of Lenawee and State of Michigan, have invented certain new and useful Improvements in Stretchers for Endless Conveyers, which are fully described in the following specification.

My invention is applicable to any endless conveyer having two aprons between which straw or like material is conveyed; but I have particularly illustrated and will describe it as applied to the elevating conveyer of a harvesting-machine.

15 In the drawings, Figure 1 is a rear elevation of a harvester-elevator with my invention applied thereto. Fig. 2 is a plan of the same. Fig. 3 is a plan of a bracket used in my invention to give bearings for certain operating parts. Fig. 4 is an elevation of a ratchet-wheel and tension-spring which I employ, the dial-covering shown in Fig. 1 being removed. Fig. 5 is a perspective of the strain-communicating lever and the links which are connected 25 with it.

A' A² are the elevator side bars, respectively front and rear.

B' B² are the endless conveying-belts of the elevator, respectively upper and lower.

30 C' C² are brackets fastened to the upper inner edges of the elevator side bars, A' A², respectively.

D is a shaft journaled in said brackets, and so extending horizontally across the elevator from front to rear.

35 E is a ratchet-wheel loose on the rear end of said shaft D. Its web constitutes the cylindrical box E', in which is coiled the spring F, secured at one end to the shaft D and at the other end to the wheel E. A pawl, e, is pivoted on the bracket C², and engages the ratchet-wheel E.

40 G G are similar links or slide-bars, in the upper ends of which the shaft of the stretching-roller B¹⁰ is journaled. The side bars, A' A², are provided with the slots a, to allow for the movement of the shaft of the roller in its adjustment, as hereinafter described, and, besides the guidance afforded the slide-bars G G 45 by the bearing of the roller shaft in said slots, they are provided, further, with the guide-

hasps a¹⁰ a¹⁰, fastened on the side bars, A' A², near the lower end of the slide bars G G.

G' G' are similar slide bars or links to the links G G, and having in their lower ends the 55 journal-bearings of the lower roller, B²⁰, which is the stretching-roller of the lower elevator-belt, B². The side bars, A' A², have the slots a' for the shaft of the stretching-roller B²⁰, and the cross-ties A³ are hollowed underneath, as 60 seen in Fig. 6, to allow both longitudinal and lateral movement to the links G' G'.

H H are equal levers, connected at one end, h h, to the upper ends of the links G' G', and at the other end, h' h', to the cables J J, which 65 are secured to and wound around the shaft D, adjacent to the brackets C' C², respectively. At h' h', midway between the points of connection to the links G' G' and the points of connection to the cables J J, said levers H H are 70 pivoted to the lower ends of the links or slide-bars G G.

The box E' in the wheel E is covered with a dial-plate, E², through which the shaft D protrudes at the center, and to the said shaft, 75 outside the dial-plate, is secured the index, finger E³. The dial is marked to indicate pounds of strain, and, as shown in the drawings, is marked from 0 to 90.

When first set up, the upper and lower elevator-belts are made of such lengths as to be equally and sufficiently tight when the shafts of their stretching-rollers B¹⁰ and B²⁰, respectively, stand about midway in the length of the slots a and a'—that is, so that the possibility 85 of adjustment in either direction shall be about equal. The tension at this position may be made as desired by rotating the ratchet-wheel E and winding up the spring F, and the lengths of the links G and G' are such that 90 when the rollers are in the position described the levers H H stand about at right angles to said links. This relation of parts is only desirable as affording the widest range of adjustment, and is not essential otherwise.

95 When any strain is put upon either of the canvas belts B' B², whether in operation or by shrinkage when not in operation, the idle-roller, around which such belt is carried, which is journaled in the slide-bars G or G', tends to 100 yield to relieve said strain, and in so yielding transmits a part of the strain, through the le-

vers H and the other slide-bars and the idle-
roller of the other belt, to said other belt.
The connection of the lever H with the cable
J becomes in that case the fulcrum of said le-
ver, and the strain is distributed between the
two belts in the inverse ratio of the lengths
of the lever-arms $h h'$ and $h' h^2$. By making
the distance $h^2 h'$ several times as great as the
distance $h h'$ the strain may be approximately
equalized. The fulcrum h' of the lever H, be-
ing a yielding fulcrum, yields when the strain
upon the belts is increased, causing the spring
F to be coiled more tightly, but preventing
by this means the excessive pressure and strain
upon the belts and their roller-bearings, which
would otherwise result when the limit of the
stretch of the belts was reached.

I claim—

1. In combination, substantially as set forth,
the stretching-rollers of the upper and lower
conveyer-belts, bars in which said rollers are
journaled, movable in the direction of the
length of the belts, levers connecting the bars
on each side, and a fulcrum for each of said
levers, supported upon the conveyer-frame
and movable relatively to its support in the
direction of the length of the belts.

2. In combination, substantially as set forth,
the stretching-rollers of the upper and lower
conveyer-belts, located at opposite ends of the
same, bars in which said rollers are journaled,
movable in the direction of the length of the
belts, levers connecting said bars and extended
from them to fulcrums supported on the frame
and movable in the direction of the length of
the belts.

3. In combination, substantially as set forth,
the stretching-rollers of the upper and lower
conveyer-belts, bars in which said rollers are
journaled, movable in the direction of the
length of the belts, levers connecting said bars,
and elastically-yielding fulcrums for said le-

vers, supported upon the frame and yielding
in the direction of the length of the belts.

4. In combination, substantially as set forth, 45
the stretching-rollers, the slide-bars having
the journal-bearings for said rollers, the levers
connecting said slide-bars, the windlass-shaft
journaled on the frame, and the cables there-
from to the levers, and suitable means to cause 50
the shaft to revolve to wind the cables.

5. In combination, substantially as set forth,
the stretching-rollers, the slide-bars having
the journal-bearings for said rollers, the levers
connecting said bars, the windlass-shaft jour-
naled on the frame, the cables therefrom to the
levers, the ratchet-wheel loose on said shaft,
and its detaining-pawl and the spring secured
to said shaft and to the ratchet-wheel. 55

6. In combination, substantially as and for
the purposes set forth, the shaft D, ratchet-wheel
E, loose on the shaft, and its pawl e, the spring
F, connecting said shaft and wheel, the move-
able stretching-roller bearings and the connec-
tion therefrom to said shaft, and a dial and 65
index-hand, one fixed on the shaft and the other
fixed on the ratchet-wheel, whereby the tension
of the conveyer-belt is indicated on said dial.

7. In combination, substantially as set forth,
the stretching-rollers, the sliding bars having 70
the bearings for said rollers, the levers con-
necting the sliding bars, the cables connected
to the ends of said levers and the windlass-
shaft D, loose ratchet-wheel E and its detent-
pawl, and the spring F, connecting the wheel 75
and the shaft.

In testimony whereof I have hereunto set
my hand, in the presence of two witnesses, at
Hudson, Michigan, this 3d day of February,
A. D. 1886.

SEYMOUR K. SEELYE.
